ALBERTO PASQUAZZO AND ANTONIO TISI, OF BUENOS AIRES, ARGENTINA.

COUPLING APPARATUS FOR RAILWAY-CARS AND THE LIKE.

1,235,238.

Specification of Letters Patent.

Patented July 31, 1917.

Continuation of application Serial No. 40,480 $\frac{1}{2}$, filed July 17, 1915. This application filed June 2, 1916.
Serial No. 101,295.

To all whom it may concern:

Be it known that we, ALBERTO PASQUAZZO and ANTONIO TISI, subjects of the King of Italy, residing at Buenos Aires, Argentina, 5 have invented certain new and useful Improvements in Coupling Apparatus for Railway-Cars and the like; and we do hereby declare the following to be a full, clear, and exact description of the invention, such as 10 will enable others skilled in the art to which it appertains to make and use the same.

The invention relates to a device for the automatic coupling of railway cars, and its principal object comprises the provision of 15 a device which facilitates the coupling of railway cars and obviates any danger hitherto connected therewith.

A further object consists in providing a locking chain at one end of the car, which 20 is adapted to enter a throat formed by jaw plates at the other car.

Still a further object is constituted by the provision of a locking bolt which, ordinarily in inoperative position, is released upon said 25 locking chain entering the throat.

Another object comprises the arrangement of thrust actuated means which release the locking bolt to lock the chain within the throat under the influence of a thrust or impact.

A still further object consists in the arrangement of means for restoring the locking bolt to inoperative position, said means being manually operated and easily accessible 35 from the sides of the railway cars.

Other objects will become apparent by reference to the specification and claims which specifically point out the scope of the invention.

40 In the drawings the preferred embodiment of the invention is illustrated.

Figure 1 is a top plan view of the coupling device, partly shown in section, and

45 Fig. 2 is a longitudinal section taken on the line C—D of Fig. 1.

The device comprises two principal parts A and B forming the coöperating elements of the coupling device. The part A embraces a coupling chain made of three inter-linked rings *a b c*, of which the first one is 50 secured to the transverse plate 1 attached to the appertaining draw bar of the railway car, while the last named ring *c* effects the coupling. To insure the proper operative 55 position of the chain, a double spiral spring

2 surrounds and supports the same, the spring being constructed and adapted to maintain the chain in horizontal position and to permit contraction or expansion of the chain under the influence of a suitable 60 force.

The part B comprises two vertical plates 3 secured together by means of three bolts *d* and nuts provided on said bolts, said plates being secured to the transverse part 1 of the 65 draw bar by means of bolts and nuts *e*. The plates 3 are recessed at their engaging faces to form a guideway for a locking lever 4, which is controlled by a plunger 5. A spring 6 interposed between the outer or rear 70 end of the plunger 5 and the part 1 normally holds the plunger in the operative or extracted position in which the plunger enters a groove in the locking lever to lock the same against vertical movement. The plunger is formed 75 with a vertical abutment adapted to be engaged by an actuating member 7 rotatably secured to an axle indicated in dotted lines in Fig. 2. The actuating member 7 projects with a finger between the abutment of the 80 plunger and a stationary lug 9, and is thus locked against rotation in the counter-clockwise direction, while its movement in the opposite direction must overcome the tension of the spring 6.

To obtain the movement of member 7, and incidentally therewith of plunger 5, a pawl *f* is rotatably secured on the axle of the actuating member 7 and is adapted and arranged to bear against a lug *g* of said member, so as 85 to rotate the latter in clockwise direction. While the movement of the pawl *f* in one direction brings it into engagement with the lug *g* of the actuating member 7, whereby the latter is rotated, rotation of the pawl *f* 90 in the opposite direction may freely take place without any effect upon the lock-controlling plunger 5. Immediately below the pawl *f* and in proper relation thereto, a cam member 8 is secured on a shaft indicated in 95 dotted lines in Fig. 2 and is constructed to assume a position under the influence of its weight in which its projection *h* does not engage the pawl *f*.

From the foregoing it is obvious that 105 when an impact or thrust is exerted upon the cam member 8, its nose *h* will bear against the pawl *f*, which latter, engaging the lug *g*, forces the projection of the actuating member 7 into engagement with the 110

projection of the plunger 5, whereby the latter is forced to the right-hand side with respect to Fig. 2, against the tension of the controlling spring 6.

5 The operation is as follows:

It be assumed that one car stands still, while the other is moving to be coupled to the other car. It be further assumed that one car either by reason of its construction, 10 or by a superposed load is about three inches lower than the other car. In approaching, notwithstanding the difference of level, the buffers of the cars will abut, while the coupling ring *c* of each car will strike the lower 15 or upper lip respectively, of the mouth formed by a projection of the draw bar plate 1 and the vertical plates 3. In the continuation of this movement the buffers compress one another, while the coupling 20 ring *c*, sliding on one lip of the mouth, strikes the cam member 8, so that the latter is rotated about its axle in a counter-clockwise direction, so as to strike in its turn against the pawl *f*, and in the continuation 25 of this movement, as obvious, the plunger 5 will be forced into the retracted position. At this juncture the locking lever 4, released from its elevated position, drops under its 30 weight until it is arrested in its fall by an upper arm coming in contact with the lower part of a bell-crank lever 12. In this lower or locking position the lever projects through the locking ring *c* of the coupling 35 chain and simultaneously has entered an opening in the projection of the draw bar plate 1. In coupling the cars, it is, of course, necessary that the spiral spring 2 allows the coupling chain to shorten itself more than the buffers compress themselves. 40 From the foregoing it is thus obvious that coupling of the cars is automatically effected by mere engagement of the buffers, so that the necessity of a man standing between the buffers is entirely eliminated. The occurrence 45 of accidents is thus practically reduced to a minimum and, in addition, the time for effecting the coupling of railway cars is materially shortened.

To uncouple the railway cars, a metallic 50 cord 10 is provided at each end of the car immediately above the buffers, which extends from one side of the car to the other and is provided at the ends with a handle 11, while staples *i* fixed at the ends of the 55 car maintain the cord in proper position and permit the transverse movement of the same for a purpose presently to be described. The inner end of the cord is secured to the upper 60 arm of the bell-crank lever 12 secured to the vertical plates 3 and to the plate 1, and controlled by a leaf spring 13 proceeding from the plate 1 and bearing against the upper arm of the lever. This arrangement permits a convenient uncoupling of railway 65 cars, which may be effected by simply seiz-

ing the handle 11 and pulling the cord 10, whereby the bell-crank lever 12 is actuated. The latter, when oscillated, lifts the locking lever 4, thus releasing the ring *c* of the coupling chain, and at the end of its upward 70 movement the lever 4 is engaged by the plunger 5, and thus the uncoupling is effected. In separating the uncoupled cars, the coupling rings leave the throat, while the cam member 8 is permitted under its 75 own gravity to return to its normal or original position, in which its nose *h* is free of engagement with the pawl *f*.

As will be seen by reference to Fig. 1, each car is provided with a mouth and a coupling chain on its draw bar plate, so that the coupling chain of one car comes into engagement with the mouth or throat of the draw bar plate on the other car. The parts A and B of the locking device are secured to the draw bar 14 by means of the bolt 15, which permits a slight rotation of the plate 1, so that the force of traction is equally divided between the parts A and B, even at times when the train moves on a curve. To 80 further equalize uneven traction forces, two small elastic plates 16 are arranged on the draw bar, which mainly serve the purpose to maintain the parts in normal position on the draw bar, preparatory and subsequent to 85 coupling.

A turn-buckle 17 permits lengthening and shortening of the draw bar, and its provision does not form part of the invention. A hook 18 is provided for coupling the cars in 100 case they are not provided with the parts A and B.

This application is a continuation of applicants' application Serial Number 40480₂, filed July 17, 1915.

105

We are aware that various changes may be made in the construction and arrangement of parts, and we do not wish to confine ourselves to the exact form as shown in the illustration, but want to avail ourselves of 110 such departures which fairly fall within the scope of the invention, as pointed out in the appended claims.

We claim:

1. In combination with the draw bars of 115 railway cars, transverse plates secured to said draw bar, a coupling chain attached to one of said plates, means for holding said chain in operative position, a pair of vertical plates forming a mouth with another of said 120 draw bar plates, a locking key reciprocatingly fitted between said pair of plates and adapted to lock said coupling chain within the mouth, means for holding said locking key in inoperative position, and means for 125 releasing said key.

2. In combination with the draw bars of 130 railway cars, transverse plates secured thereto, an expansible coupling chain attached to one of said plates, means for hold-

130

- ing said chain in horizontal position and permitting its contraction and expansion under the influence of a force, a pair of vertical plates forming a throat with another 5 of said draw bar plates and being secured thereto, a locking member reciprocatingly fitted between said pair of plates and adapted to lock said chain in said throat, means for holding said locking lever in 10 operative position, and means for releasing said lever.
3. In combination with the draw bars of railway cars, plates secured thereto, a coupling chain attached to each of said 15 plates but on opposite sides of said draw bars, means for holding said coupling chains in horizontal position, a pair of vertical plates secured to each of said draw bar plates opposite to said coupling chain, said 20 pairs of plates forming a mouth with the respective draw bar plates to provide for the reception of the coupling chains, a locking lever reciprocatingly fitted between said 25 plate pairs and adapted to lock said chain in said mouth after introduction therein, means for holding said locking lever in inoperative position, and means for releasing said locking lever.
4. In combination with the draw bars of 30 railway cars, transverse plates secured to said draw bars, a coupling chain attached to one of said plates, yieldable means for holding said chain in horizontal position, a plurality of vertical plates secured to and forming 35 with the other of said draw bar plates a throat, and automatic means for locking said chain in said throat.
5. In combination with the draw bars of railway cars, transverse plates secured to said draw bars, a coupling chain attached 40 to one of said plates, yieldable means for holding said chain in horizontal position, a plurality of plates secured to and forming with the other of said draw bar plates an open throat, and chain-operated means for 45 securing said chain within said throat.
6. A coupling device for railway cars, comprising in combination with the draw bars, transverse plates secured thereto, a coupling chain and a pair of vertical plates 50 respectively secured to the draw bar plates on each side thereof, so that the chain of one draw bar plate is opposed to the pair of plates of the other draw bar plate, said pair of plates forming a throat with said draw 55 bar plates to receive the appertaining coupling chain, yielding means for holding said coupling chain in proper position, and thrust actuated means for locking said chain in said throat. 60
7. In combination with the draw bars of railway cars, plates secured to said draw bars, a coupling chain attached to one of said plates, means for holding said chain in operative position, a plurality of vertical 65 plates secured to the other of the draw bar plates and forming an open throat with an extension thereof, thrust-operated means for locking said chain in said throat, and manually operated means for disengaging 70 said chain, substantially as described.
